FIG. 1

FIG. 2

FIG. 3

FIG. 7

FIG. 4

FIG. 5

FIG. 6

FIG. 1 is a perspective view of a combined whistle and bubble toy pipe embodying the preferred embodiment of the present invention and having a bowl in the configuration of a parrot head.

FIG. 2 is a front view of the pipe shown in FIG. 1.

FIG. 3 is a rear view of the pipe shown in FIG. 1.

FIG. 4 is a side view of the pipe shown in FIG. 1. The side opposite that shown in FIG. 2 is the mirror image thereof.

FIG. 5 is a top view of the pipe shown in FIG. 1.

FIG. 6 is a bottom view of the pipe shown in FIG. 1.

FIG. 7 is a perspective view of a modified embodiment of the invention in which the opening adjacent the mouth-piece is oval rather than square, in which the eye has a slightly different appearance and in which the bottom of the mouth is formed slightly differently. Other than

in these respects the modified embodiment is the same as the preferred embodiment.

I claim:

The ornamental design for a combined whistle and bubble toy pipe, as shown and described.
